(57) **CLAIM**

The ornamental design for a shoe, as shown and described.

DESCRIPTION

FIG. 1 is a front perspective view of a shoe showing our new design;

FIG. 2 is a side view thereof;

FIG. 3 is a rear perspective view thereof;

FIG. 4 is a front perspective view of an alternate embodiment of a shoe showing our new design;

FIG. 5 is a side view thereof; and,

FIG. 6 is a rear perspective view thereof.

The contrast in shading between the three regions represents a contrast in appearance only and does not represent any particular color, material, texture or finish. The broken lines immediately adjacent to the periphery of the shaded area define the bounds of the claimed design and form no part thereof. The broken lines depicting the remainder of the shoe show features that form no part of the claimed design.
